US0D1063358S

(12) **United States Design Patent** (10) **Patent No.:** **US D1,063,358 S**
(45) **Date of Patent:** **** Feb. 25, 2025**

(54) **FOOTWEAR ARTICLE**

(71) Applicant: **SALOMON S.A.S.**, Epagny Metz-Tessy (FR)
(72) Inventor: **Gia Dat Hoang**, Villaz (FR)
(73) Assignee: **Salomon S.A.S.**, Epagny Metz-Tessy (FR)

(**) Term: **15 Years**

(21) Appl. No.: **29/884,156**

(22) Filed: **Feb. 8, 2023**

(30) **Foreign Application Priority Data**

Oct. 7, 2022 (WO) WIPO123480

(51) **LOC (15) Cl.** **02-04**
(52) **U.S. Cl.** **D2/972**

(57) **CLAIM**

The ornamental design for a footwear article, as shown and described.

DESCRIPTION

FIG. 1 is a front, first side perspective view of a footwear article showing my new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The ornamental design that is claimed is shown in the images in the drawings. The even dashed broken lines in FIGS. 1 through 7 are directed to environment and form no part of the claimed design.

1 Claim, 6 Drawing Sheets
